(57) **CLAIM**

The ornamental design for the golf club head, as shown and described.

DESCRIPTION

FIG. 1 is a top isometric view of a golf club head showing my new design;

FIG. 2 is a bottom isometric view of the golf club head of FIG. 1;

FIG. 3 is a front elevation view of the golf club head of FIG. 1;

FIG. 4 is a rear elevation view of the golf club head of FIG. 1;

FIG. 5 is a top plan view of the golf club head of FIG. 1;

FIG. 6 is a bottom plan view of a golf club head of FIG. 1;

FIG. 7 is a right side elevation view of the golf club head of FIG. 1;

FIG. 8 is a left side elevation view of the golf club head of FIG. 1; and,

FIG. 9 is a cross-sectional view of the golf club head of FIG. 1, taken along line 9-9 of FIG. 5.

The features shown in broken lines in the drawing depict portions of the design that form no part of the claimed design.

1 Claim, 5 Drawing Sheets
